SUPPORT

Clinton W. Kneff, Bridgeville, Pa.

Application March 19, 1935, Serial No. 11,836

4 Claims. (Cl. 211—74)

This invention relates to supports, and more particularly to those which are used for holding burettes and similar laboratory equipment, although not limited thereto.

5 In using various types of laboratory equipment, such as burettes and the like, considerable expense and trouble is brought about by breakage, due to the many failings of the supporting devices of the prior art. One of the inherent characteristics of such devices is that they lose efficiency under relatively heavy loads; or from long periods of usage. There have been numerous attempts to device a support of this type which will obviate these disadvantages, but until 10 the present time none have been met with material success.

It is one of the objects of the present invention to provide a novel support which is particularly adapted for holding burettes and the like, 15 and which operates in a highly efficient manner whether the load is heavy or otherwise.

Another object is to provide a novel and inexpensive support of the class described which is light in weight, extremely simple in operation, 20 and one which will prove to be very durable in service.

These and further objects will be apparent after referring to the drawing, in which:

Figure 1 is a side elevation of the device of the 30 invention.

Figure 2 is a fragmentary end elevation.

Figure 3 is a plan.

Referring more particularly to the drawing, the numeral 2 designates a vertical base member 35 which is adapted to carry the various elements of the device of the invention. The base member 2 is suitably secured to, or otherwise carried by, a base 3 which is adapted to rest upon a table, or bench.

40 The vertical base member 2 is provided with a pair of upper and lower relatively aligned studs, or rivets, as at 5 and 6, respectively.

A curved lever 7 is pivotally mounted adjacent one of its ends 8 to the stud 5, and has on its 45 other end a downwardly curved extension 9.

A lever 12 is pivotally mounted adjacent one of its ends 13 to the stud 6, and while of substantially the same length is preferably straight in lieu of the curved construction of the lever 7.

50 The levers 7 and 12 are extended angularly from the base member 2 and connected in spaced relationship by a link 14, through suitable studs, or rivets, as at 15 and 16, respectively. The connection of the stud 15 to the curved lever 7 is between its end 8 and downwardly curved extension

9, while the connection of the stud 16 to the lever 12 is in vertical alinement with the stud 15. This provides a straight extension 17 on the end of the lever 12 opposite its pivoted end 13, which serves as a handle-portion. 5

Each of the upper and lower ends of the link 14, which are indicated at 18 and 19, respectively, carries a right-angularly extending gripping member 20 which is secured thereto by an integral deformable shank 21 on one of its ends. The 10 gripping members 20 are substantially V-shaped in a horizontal plane, as shown at 22, and are relatively aligned with respect to the vertical.

The downwardly curved extension 9 of the curved lever 7 carries a right-angularly extending straight gripping member 23, which is secured thereto by an integral deformable shank 24 on one of its ends. 15

The pair of gripping members 20 on the link 14 and the single gripping member 23 on the 20 downwardly curved extension 9 of the curved lever 7 are all preferably covered with rubber, or a like substance, as indicated at 26.

In operation, the straight extension or handle-portion 17 of the lever 12 is raised which, through 25 the link 14, raises the curved lever 7. This movement causes the downwardly curved extension 9 of the curved lever 7 to move away from the link 14 in an arcuate path.

A burette X, or similar piece of equipment, is 30 placed in the V-shaped portions 22 of the vertically aligned gripping members 20, and the handle-portion 17 of the lever 12 lowered. The lowering of the handle-portion 17 causes the downwardly curved extension 9 of the curved 35 lever 7 to move toward the link 14 in an arcuate path. As this movement of the downwardly curved extension 9 is continued, the single and straight gripping member 23, which is carried thereby, is brought into contact with the burette 40 X on its side opposite the gripping member 20, and intermediate the latter.

It will be seen that, due to the arcuate movement of the downwardly curved extension 9 of the curved lever 7, the burette X will be gripped 45 with a pressure directly commensurate with its weight. This movement of the downwardly curved extension 9, together with the simultaneous downward movement of the link 14, permits the device of the invention to efficiently grip and 50 support loads ranging from the lightest and thinnest thermometer to a large and most heavily laden burette.

While I have shown and described certain specific embodiments of my invention, it will be 55

understood that I do not wish to be limited exactly thereto, since various modifications may be made without departing from the scope of my invention, as defined by the following claims.

5 I claim:

1. A support for burettes and the like, comprising a base member, a curved lever pivotally mounted on said base member and arranged to extend angularly therefrom, a gripping element carried by said curved lever remote from its pivotal mounting, a second lever pivotally mounted on said base member and arranged to extend angularly therefrom, a link connecting said levers, and a plurality of substantially spaced gripping elements carried by said link.
- 10 2. A support for burettes and the like, comprising a base member, a curved lever pivotally mounted on said base member, a gripping element carried by said curved lever, a second lever pivotally mounted on said base member in spaced relationship with respect to said first named lever, a link connecting said levers, said link being arranged in substantial parallelism with said base member, and a plurality of substantially spaced gripping elements carried by said link.
- 15 3. A support comprising a base member, a lever pivotally mounted on and extending an-

gularly from said base member, a second lever pivotally mounted on and extending angularly from said base member, said second named lever being in spaced relationship with respect to said first named lever, a pivoted link connecting said levers, at least one gripping element carried by one of said levers, and at least one gripping element carried by said link, said levers and link being movable in a plane which is substantially co-extensive with the axis of the object to be supported.

4. A support comprising a base member, a lever pivotally mounted on and extending angularly from said base member, a second lever pivotally mounted on and extending angularly from said base member, said second named lever being in spaced relationship with respect to said first named lever, a pivoted link connecting said levers in spaced relationship, said link having an extension from each of said levers, a gripping element carried by each of said extensions, and a gripping element carried by said link, said levers and link being movable in a plane which is substantially co-extensive with the axis of the object to be supported.

25 CLINTON W. KNEFF.
